PORTABLE FABRIC STEAMER

Walter S. Marvin and Carl L. Sibenhorn, Two Rivers, Wis., assignors to Metal Ware Corporation, Two Rivers, Wis.

Application March 23, 1931. Serial No. 524,650

4 Claims. (Cl. 219—38)

This invention relates to improvements in a portable fabric steamer.

One of the objects of the present invention is the provision of a portable fabric steamer including a boiler electrically heated and provided therein with a steam conduit having one end thereof leading out through the top of the boiler for projecting steam onto fabrics, such as plush, velvet, and the like, to bring the nap in cases where it has been flattened, due to folding, etc., and also includes means whereby the device can be readily supported by the hand for discharging steam onto the fabrics in the proper places.

Another object of the present invention is the provision of a device of the above character, wherein steam will be highly vaporized and provide a fine spray of steam to be directed onto fabrics, such as velvet, plush, and the like, for raising the nap and wherein the water from which the steam has developed, is electrically heated and at the same time includes a detachable handle carried by the body of the device so that the same can be readily guided for projecting the steam onto the fabrics.

A further object of the present invention is the provision of a device of the above character including a boiler body having an electrical heating element in the bottom thereof for generating steam within the boiler body, and also includes a tubular conduit leading from a point adjacent the top of the boiler down to close proximity to the heater, and then coiled with the second end projecting out through the top of the boiler for the discharge of the steam, whereby the steam is superheated by the hot water as it passes through the tubular conduit.

A still further object of the present invention is the provision of a steamer of the above character, wherein the inlet of the steam conduit is positioned at the opposite side of the boiler from the outlet, so that when the device is tilted for directing the steam onto the fabrics, the water within the boiler will not enter the conduit, whereby the boiler may be disposed at various angles without any water entering the inlet end of the conduit.

With the above and other objects in view, which will appear as the description proceeds, the invention resides in the novel construction, combination and arrangement of parts substantially as hereinafter described and more particularly defined by the appended claims, it being understood that such changes in the precise em-

bodiment of the herein disclosed invention may be made as come within the scope of the claims.

Figure 1 is a vertical sectional view through the body of the device, with parts thereof illustrated in elevation;

Figure 2 is a bottom plan view, with parts thereof broken away.

In carrying out our invention, the device includes a cylindrical body 1 which forms the boiler of the device, wherein the steam is generated.

Extending into the bottom of the body 1 is a cylindrical member 2, the inner closed end of which is positioned inwardly of the body 1, while the edges are disposed at right angles, as shown at 3, and then bent upwardly around the lower end of the body 1, as shown at 4, and then extended laterally and provided with apertures to provide a securing flange.

The base 5 is formed of a single piece of material having its lower edges outwardly curved, as shown at 6, with the extreme edge turned upwardly to form a bead 7. The bottom plate 8 is provided with supporting feet 9 of insulating material and the plate 8 is connected to the upturned edge of the flange 6 by means of screws 10. Arranged within the cylindrical member 2 is a heating unit 12 connected up by means of the conductors 13 to the contact points 14, arranged within the socket 15.

At the upper end of the boiler 1, we provide a sleeve 16 internally threaded to receive the headed plug 17 which has a bore 18 leading from the inner end thereof, and which communicates with an aperture in the outer end of the plug. 90 Slidably mounted within the bore 18 is a pin 19 having stop nuts 20, on the inner end, and a head 21 on the outer end. Mounted upon the pin 19 and disposed between the inner end of the bore 18 and the nuts 20, is a coil spring 22 which normally urges the head 21 towards a seated position. The pin 19 carries a washer 23 positioned beneath the head 21, so as to form a tight closure for the aperture in the end of the plug 17. The plug 17 is provided with laterally disposed ears 24 forming thumb pieces whereby the same may be screwed into the sleeve 16, or removed therefrom.

The movable pin 19 forms a safety valve for the body of the boiler whereby, when the steam pressure within the boiler reaches a predetermined pressure, the head 21 will be unseated, permitting the steam to pass upwardly through the bore 18 and out through the aperture in the outer end of the plug. In order to determine the water level 110

within the boiler body 1, lateral pipes 25 and 25' are connected up with the body 1 at suitable points as indicated in Figure 1, and these pipes are connected by means of a gage glass 26.

5 One of the main features of our invention is the arrangement of the steam conduit 27, wherein one end of the tube opens into the boiler adjacent the upper end thereof, as indicated at 28. The tube then extends downwardly to a point adjacent 10 the heating element 12. The tube is then coiled, as shown at 29, and passes out through the top of the boiler upon the side thereof opposite the inlet end 28 and extends laterally at an angle relative to the body of the boiler to form a discharge nozzle 30. It will be apparent from this arrangement that when the boiler 1 is tilted to guide the discharge nozzle 30 over the surface of the fabrics, the water within the boiler will not enter the inlet end 28 of the tube. However, by 20 causing the steam to travel downwardly and then around through the coil 29, the steam, through the medium of the water within the boiler will be superheated and will be highly vaporized by the time it passes out through the nozzle 30, resulting in a fine spray of steam being discharged 25 onto the fabrics.

One side of the boiler 1 is provided with internally threaded reinforced portions 31 to which the frame 32 for the handle 33 is connected, by 30 means of the screw bolts 34. Suitable insulating washers 35 can be mounted upon the shanks of the bolts 34 and positioned between the frame 32 and the outer faces of the reinforced portions 31.

From the above description taken in connection 35 with the accompanying drawing, it will be readily apparent that we have provided a very simple and inexpensive device which will prove very efficient for the purpose intended, generating, by electrically heating, a very fine spray of steam, 40 which is superheated by passing the same through the hot water in the boiler. This device has been found to be very useful in steaming fabrics, such as plush, velvets, and the like, for raising the nap thereon, which is usually pressed down through 45 the folding of the goods.

Various types of bottom members can be used for supporting a device upon any surface, but it is preferred to have a bottom member which is inserted in spaced relation with the surface, so 50 that the heat from the electric heating element will not injure a highly polished surface.

Various types of heating elements can be used, but it is preferred to provide a heating element which can be installed within an enclosed chamber in the bottom of the boiler, so that the water within the boiler will be inwardly heated and maintained at a boiling point in order to develop sufficient steam for the purpose intended. It will also be noted that when the steam reaches a 60 predetermined pressure it will pass out through the safety valve at the top of the boiler.

While we have shown and described the preferred embodiment of our invention, it will be apparent from the foregoing that slight changes may be made in the construction when putting the invention into practice without departing from the spirit of the same or the scope of the appended claims.

We claim:

1. A device of the character described including a boiler body, an inwardly extending bottom member therefor, a heating element in the bottom member, a base member, insulated feet attached to the base, a steam conduit in the boiler having the inlet end positioned adjacent the top at one side and the outlet end extending out through the top on the side of the boiler opposite the inlet and a handle connected to one side of the body. 80

85

90

95

2. A device of the character described including a cylindrical body, an inwardly extending bottom member therefor, a heating element carried by the bottom, a steam conduit having its inlet end arranged adjacent the top of the body at one side thereof, said conduit extending into the body adjacent the bottom and then coiled and extended upwardly, the outlet end of said conduit leading out through the top of the body at the side thereof opposite the inlet and a laterally disposed nozzle at the outlet end. 100

105

3. A device of the character described including a cylindrical body, a heating element arranged in the bottom thereof, a steam conduit within the body having its outlet end adjacent the top of the body and at one side thereof, said conduit extending downwardly to a point adjacent the bottom and coiled with the coils extending upwardly, the outlet end of said conduit extending through the top of the body at the side thereof opposite the inlet, a safety valve removably positioned in the top of the body and a removable handle attached to the side of the body and arranged upon the opposite sides of the outlet of the steam conduit. 110

115

4. A portable device for steaming fabrics comprising a boiler body, an electrical heating element disposed in the lower end of the body, a steam conduit pipe disposed in the boiler body having its inlet positioned adjacent to the top of the boiler above the water level of the boiler and at one side of the longitudinal axis of the boiler, and a laterally extending outlet formed on the 120 steam conduit extending out through the top of the boiler on the side of the boiler opposite to the inlet whereby upon the tilting of the boiler toward said outlet, the water will gravitate away from the inlet, and a manipulating handle connected with the body. 125
